DESIGN FOR A CUTTING TORCH

Elmer H. Smith, Minneapolis, Minn., assignor to
Smith Welding Equipment Corporation, Min-
neapolis, Minn., a corporation of Minnesota

Application March 13, 1939, Serial No. 83,529

Term of patent 7 years

To all whom it may concern:

Be it known that I, Elmer H. Smith, a citizen of the United States, residing at Minneapolis, in the county of Hennepin and State of Minnesota, have invented a new, original, and ornamental Design for Cutting Torches, of which the following is a specification, reference being had to the accompanying drawing, forming part thereof, and in which

Figure 1 is a side elevational view of a cutting torch showing my new design;

Figure 2 is a top view thereof; and
Figure 3 is an end view of the torch.
The dominant features of my design reside in
the portions shown in full lines.

I claim:

The ornamental design for a cutting torch,
substantially as shown, and described.

ELMER H. SMITH.
